UNITED STATES PATENT OFFICE.

ARTHUR H. SKAER AND OMAR E. CLARK, OF DENVER, COLORADO, ASSIGNEES TO THE DENVER ROCK DRILL MANUFACTURING COMPANY, OF DENVER, COLORADO, A CORPORATION OF DELAWARE.

DRILL-STEEL-SHARPENING APPARATUS.

Application filed April 24, 1923. Serial No. 634,295.

To all whom it may concern:

Be it known that we, ARTHUR H. SKAER and OMAR E. CLARK, citizens of the United States, residing at Denver, in the county of Denver and State of Colorado, have invented certain new and useful Improvements in Drill-Steel-Sharpening Apparatus, of which the following is a specification.

The object of the present invention is to provide a very compact, simple and highly effective machine for the above purpose.

In the accompanying drawings:

Figure 1 is a side elevation of the preferred embodiment of the invention, 15 Figure 2 is a rear elevation of the same, with one of the closure plates removed,

Figure 3 is a front elevation with the closure plate removed,

Figure 4 is a vertical longitudinal sectional view,

Figure 5 is a detail vertical sectional view through the clamping die motor and the controlling valve,

Figures 6 and 7 are detail sections 25 through the valve mechanism, showing the valve in different positions,

Figure 8 is a detail sectional view of a portion of the valve chest and the receiving funnel for the exhaust.

30 In the structure disclosed, a hollow base member is employed, preferably comprising a bottom 9, upright side walls 10, and a relatively heavy top 11 which constitutes a platform. A vertical transverse web or reinforcing partition 12 extends from the bottom 9 to the top 11, and from one side wall to the other, said partition having an opening 13 in its upper portion. As a consequence the base has a chamber of relatively great size, and forms a casing provided with opposite open sides. These sides are adapted to be closed by plates 14 and 15, detachably secured in place by screws 16 engaging inset lugs 17 carried by the side walls 10.

One end of the platform 11 is provided with an elevated portion 18, forming a seat for a fixed clamping die 19 that may be of any desired character. Mounted to reciprocate in the platform 11 on opposite sides of the die 19, are spaced vertically disposed plunger rods 20, having their upper ends connected by a cross head 21, carrying a movable die 22 that cooperates with the die

19 in a manner well understood. These 55 plunger rods 20 extend downwardly into the chamber of the base member on one side of the partition 12, and preferably have their lower ends slidably in bearing portions 23 projecting upwardly from the bottom 9. 60 The lower end portions of the plunger rods 20 above the bearing portions 23 are connected by a cross head 24.

Depending from the platform top 11 are spaced lugs 25, and fulcrumed between its 65 ends on said lugs and extending between them, is a lever 26, the fulcrum being designated 27. The arm of the lever that is located between the partition 12 and the closure plate 15, is connected by a pitman 28 70 with the cross head 24 of the plunger rods 20. The other arm of said lever extends through the opening 13 in the partition 12 and has pivoted thereto another pitman 29. This pitman extends into a tubular hollow piston 30, and is pivoted, as shown at 31, to its inner or lower end. The piston 30 is contained in a vertical cylinder member 32 housed within the chamber of the base member and detachably mounted therein. To this end the cylinder member includes a lower head 33, and the cylinder or barrel has an outstanding flange 34 located on the head. Through the flange 34, the head 33 and the bottom 9 are passed holding bolts 35 that serve to secure the cylinder in place. The upper end of the cylinder has a contracted portion 36, forming an upper head, and the piston has an upper flange pressure surface 37, forming with said head 36 an upper pressure space 38. 85

Located upon one side of the cylinder member 32 and preferably integral therewith, is a valve chest 39, the upper portion 40 of which constitutes what may be termed a pressure chamber. Opening into this pressure chamber is a motive fluid supply port 41 with which communicates a supply pipe 42 connected with any suitable source of fluid under pressure, preferably air. From this chamber 40 a constant pressure supply port 43 opens into the upper pressure chamber 38 of the cylinder 32. Below the ports 41 and 43 is a supply port 44, communicating with a passageway 45 that leads into the bottom of the cylinder member below the head of the piston 30. 95

100 Mounted on the rear portion of the plat-

form 11 is a fluid-operated dollying hammer of any suitable construction, the motor thereof being shown and generally designated by the reference numeral 46. A dolly 47, actuated by the hammer, is adapted to operate upon a drill steel or other work clamped by the dies 19 and 22, as will be obvious. The supply to the dollying hammer is delivered from the valve chest 39 through a conduit 48, connected to said dollying hammer, the supply port 50 from said valve chest 39, being located below the port 44, through which motive fluid is supplied to the die actuating motor. The lower end of the valve chest 39 is open, as shown at 51 and constitutes an exhaust port.

Mounted within the chamber of the base member in line with said exhaust port 51, but slightly spaced therefrom is the open mouth of a receiving funnel 52, the neck 53 of which is coupled to a hose 54 arranged within the base member chamber, preferably extending through the lower end of the partition 12. This hose leads to a transverse manifold 55, two branches 56 of which constitute, in effect, ports that open between the clamping dies 19 and 22, preferably on opposite sides of their work-engaging faces.

Located in the bore of the valve chest 39 is a reciprocating plunger valve, comprising a lower controlling head 57 connected by a neck 58 with an upper closure head 59, the heads 57 and 59 constituting, in effect, the end walls or closures of the pressure chamber 40 of the valve chest. Pivotaly connected to the upper end of this valve is a link 60 connected to the crank arm 61 of a rock shaft 62 journaled in one of the side walls 10 of the base member. On the outer end of said rock shaft is fixed an actuating crank 63, the movement of which is limited by a suitable quadrant 64. The weight of the valve and the movable parts coacting therewith is substantially counterbalanced, preferably by a coiled spring 65 secured to the link 60 and to a hook 66 or other device on the partition 12.

The operation of the structure is as follows: Assuming air or other expansible fluid, under pressure, is supplied to the pipe 42, this fluid will be in the chamber 40, and consequently through the port 43 will have free access to the chamber 38, thus acting on the upper surface 37 of the piston 30, and forcing it to its lowermost position. With the valve as shown in Figure 5, the ports 44 and 50 are cut off from the chamber 40. If now the handle crank 63 is moved to depress the valve, the controlling head 57 will move downwardly until the port 44 is opened to the supply port 41 through the pressure chamber 40. Consequently motive fluid will flow into the cylinder member below the piston, and overcoming the pressure against the surface 37, will elevate said piston. As

a consequence the lever 36 will be swung on its fulcrum, causing the depression of the cross head 24, the plunger rods 20 and the upper movable die 22. If therefore work has been placed between these dies, said work will be clamped thereby in a position to be operated on by the dolly 47. A continued downward movement of the valve will next bring the port 50 into open communication with the supply of motive fluid, and therefore motive fluid will be turned into the dollying hammer so that the work clamped will be operated on. A retrograde or upward movement of the valve will first shut off the supply to the dollying hammer, thereby causing it to cease work and afterwards the supply to the die actuating motor through the passageway 45 will be cut off from the supply. When this occurs, the exhaust port 51 will be opened to the passageway 45 and the pressure on the upper face 37 of the piston will cause the said piston to move downwardly, thereby elevating the upper or movable holding die 22. As said die moves upwardly, the exhaust taking place through the port 51 will be in great measure received by the funnel 52, and passing through the hose 54 and manifold 55, will escape between the dies, thereby cleaning the same from scale and other detritus. Inasmuch, however, as the conduit 54 will not immediately receive and transmit the full amount of the expanding exhaust, a portion will escape into the main chamber of the base member, which having a relatively great capacity will cause a slight increase above atmospheric pressure, and yet not enough to create any material back pressure that will affect the proper opening action of the die operating motor, and as soon as the pressure in the conduit 54 decreases the slight pressure that has been built up in the base chamber will cause the flow of the exhaust motive fluid from the chamber into the funnel 52 so that it will escape also between the holding dies and supplement the cleaning action.

Obviously the structure is simple, and it has proven highly effective for the purposes disclosed. It is very compact, the operating mechanism for the movable die being located wholly beneath the table carrying the dies and dollying hammer. Moreover the movable parts are readily accessible, the plunger rods and lever being available by the removal of the closure plate 15, and the die moving motor being likewise easily accessible by removing the face plate 14. This motor being an entity separate from the base member, can be constructed and assembled with ease and expedition.

From the foregoing, it is thought that the construction, operation and many advantages of the herein described invention will be apparent to those skilled in the art, with

out further description, and it will be understood that various changes in the size, shape, proportion and minor details of construction, may be resorted to without departing from the spirit or sacrificing any of the advantages of the invention.

Having thus fully described our invention, what we claim as new, and desire to secure by Letters Patent, is:—

1. In a drill sharpening apparatus, the combination with a hollow base having a bottom and a top that constitutes a platform and providing a chamber therebeneath having an open side, of a fixed die on the platform, a movable die cooperating with the fixed die, a carrier for the movable die extending downwardly into the chamber, a cylinder member mounted upon the bottom and located in the chamber, said cylinder member being accessible and removable through the open side, a piston in the chamber, and means in the chamber connecting the piston and carrier to operate the latter by the former. 70
2. In a drill sharpening apparatus, the combination with a hollow base having a bottom and a top that constitutes a platform and providing a chamber therebeneath having an open side, of a fixed die on the platform, a movable die cooperating with the fixed die, a carrier for the movable die extending downwardly into the chamber, a cylinder member mounted on the chamber, a piston in the cylinder member, a lever in the chamber fulcrumed between its ends on the base, a connection between the piston and one arm of the lever, and a connection between the other arm of the lever and the carrier. 75
3. In a drill sharpening apparatus, the combination with a hollow base providing a chamber and having a top wall constituting a platform, of a fixed die on the platform, upright reciprocating carrier rods in the chamber projecting above the platform on opposite sides of the fixed die, a die mounted on the projecting portions of the rods and cooperating with the fixed die, a lever fulcrumed between its ends in the chamber, a cross head connecting the rods with the chamber and connected to one end of the lever, and an upright motor in the chamber having a piston connected to the other end of the lever. 80
4. In a drill sharpening apparatus, the combination with a hollow base member comprising a top, a bottom, opposite open sides and an intermediate upright partition between the bottom and top, a fixed die on the top, a movable die coacting with the fixed die, a movable carrier for the die extending into the base on one side of the partition, a motor mounted in the base on the other side of the partition, a lever in the base fulcrumed between its ends there- 85
- on and extending through the partition, a connection between one end of the lever and the motor, and a connection between the other end of the lever and the carrier. 90
5. In a drill sharpening apparatus, the combination with a hollow base member constituting a casing having a top, a bottom and opposite open sides, of a fixed die and a coacting movable die mounted on the top of the casing, a motor mounted upon the bottom within the casing and accessible through one of the open sides, and actuating means for the movable die within the casing and operated by the motor, said actuating means being accessible through the other open side. 95
6. In a drill sharpening apparatus, the combination with a hollow base member constituting a casing and having opposite open sides and an intermediate reinforcing partition, the top of said base member constituting a platform, of a fixed die on the platform, upright reciprocating plunger rods extending through the platform on opposite sides of the fixed die and having portions within the casing on one side of the partition, a movable die carried by the projecting portions of the rods and coacting with the fixed die, a cross head connecting the rods with the casing and accessible through one of the open sides, a lever fulcrumed between its ends in the casing transversely of the partition, a pitman connecting one end of the lever and the cross head, an upright cylinder in the casing on the opposite side of the partition to the cross head and plunger rods, a piston in the cylinder, a pitman connecting the piston and the opposite end of the lever to the first pitman, and detachable closures for the open sides of the casing. 100
7. In a drill sharpening apparatus, the combination with coacting dies, of a motor for relatively moving the same, means for admitting motive fluid to the motor and permitting its exhaust, and a conduit having a receiving mouth in line with the exhaust and an outlet delivering to the dies, said mouth permitting the escape of excess exhaust. 105
8. In a drill sharpening apparatus, the combination with coacting dies, of a motor for relatively moving the same, means for admitting motive fluid to the motor and permitting its exhaust, and a conduit having a funnel form receiving mouth in line with but spaced from the exhaust permitting means, said conduit delivering to the dies. 110
9. In a drill sharpening apparatus, the combination with a hollow base member having a closed chamber, of relatively movable dies mounted on the base member, a motor for relatively moving the dies, means for supplying motive fluid to the motor and permitting its exhaust, and means for re- 115
- 120
- 125
- 130

ceiving a portion of the exhaust directly from the exhaust permitting means and directing as a cleaning agent to the dies, allowing the initial escape of the remainder of the exhaust into the chamber and utilizing the said exhaust that escapes into the chamber for die cleaning purposes.

10. In a drill sharpening apparatus, the combination with a hollow base member having a closed chamber, of relatively movable dies mounted on the base member, a motor for relatively moving the dies, means for supplying motive fluid to the motor and permitting its exhaust, and means for receiving a portion of the exhaust directly from the exhaust permitting means and directing as a cleaning agent to the dies, allowing the initial escape of the remainder of the exhaust into the chamber and admitting said escaped exhaust into the directing means for die cleaning purposes.

11. In a drill sharpening apparatus, the combination with a hollow base member having a closed chamber, of relatively movable dies mounted on the base member, a motor for relatively moving the dies, valve controlled means in the chamber for supplying motive fluid to the motor and permitting its exhaust, said means having an exhaust port in the chamber, and a conduit having an exhaust receiving funnel in line with the exhaust port, said conduit having outlet ports delivering to the dies.

12. In a drill sharpening apparatus, the combination with a hollow base member having a closed chamber, of relatively movable dies mounted on the base member, a motor in the chamber for relatively moving the dies, valve controlled means in the chamber for supplying motive fluid to the motor and permitting its exhaust, said means having an exhaust port in the chamber, and a conduit having an exhaust receiving funnel in line with but spaced from the exhaust port, said conduit having outlet ports delivering to the dies.

13. In a drill sharpening apparatus, the combination with relatively movable work-clamping dies, of a motor for moving the

same, a fluid actuated dollying hammer for the work clamped by the dies, a valve chest common to the motor and hammer, and having a motive fluid supply receiving port, an outlet supply port in communication with the dollying hammer and a second outlet supply port in communication with the motor and located between the first two ports, and a reciprocatory plunger valve in the chest and movable in one direction to a position that cuts off communication between the supply receiving port and the other two ports and in the opposite direction to successively uncover to the receiving port, the outlet supply port to the motor and the outlet supply port to the dollying hammer and on a reverse movement to close them in reverse order.

14. In a drill sharpening apparatus, the combination with relatively movable work-clamping dies, of a motor for moving the same, including a cylinder member and a piston operating therein and having opposed pressure surfaces, a fluid actuated dollying hammer for the work clamped by the dies, a valve chest common to the motor and hammer and mounted on the cylinder member, said chest having a live fluid pressure chamber with a supply port leading thereto and a pressure port leading therefrom to the interior of the cylinder member on one side of the piston therein, said valve chest having another pressure port leading therefrom to the opposite side of said piston, a conduit leading from the valve chest on the outer side of the second pressure port, and a reciprocatory plunger valve in the chest that is movable to successively open the second pressure port and conduit to the pressure chamber in the order named and to close them in the reverse order.

In testimony whereof, we affix our signatures in the presence of two witnesses.
